UNITED STATES PATENT OFFICE.

THOMAS PENN AND ALFRED EDWARD PENN, OF WANDSWORTH ROAD,
COUNTY OF SURREY, ASSIGNEES TO THE PENN LAMP AND LIGHTING
COMPANY, LIMITED, OF LONDON, ENGLAND.

OIL-LAMP.

SPECIFICATION forming part of Letters Patent No. 431,616, dated July 8, 1890.

Application filed January 24, 1890. Serial No. 337,944. (No model.)

To all whom it may concern:

Be it known that we, THOMAS PENN and ALFRED EDWARD PENN, subjects of the Queen of Great Britain, both residing at 40 Westbury street, Wandsworth Road, in the county of Surrey, England, have invented certain new and useful Improvements in Oil-Lamps, of which the following is a specification.

Our invention has for its object to provide
10 a simple and cheap oil-lamp in which heavier
oils can be burned than can be burned in
lamps as generally hitherto constructed. Ac-
cording to our invention, we provide, in con-
nection with the burner, (which contains the
15 wick,) a tube or passage or tubes or passages
which at its or their lower end or ends dips
or dip into the oil in the reservoir, and at its
or their upper end or ends deliver the said
oil into a chamber or chambers surrounding
20 or partly surrounding the upper end of the
wick-tube and communicating with the wick
therein by perforations in the said tube.

We place in the chamber or chambers into
25 which the oil passes, as aforesaid, an absorb-
ent material. We find that the material
known as "fustian" or "mole-skin" answers
this purpose. The said absorbent material
covers the opening or openings in the wick-
30 tube, and may either fill the chamber or
chambers or be placed in a space between the
perforated upper part of the wick-tube and a
perforated plate or plates situated in the said
chamber or chambers.

The wick may or may not dip into the oil,
35 and a feeding-wick may, if desired, be used,
which, being made of a more porous or open
texture than the main wick, will cause a suffi-
cient quantity of oil to pass up to the main
wick to keep it moist, although not sufficient
40 to supply the burner. The aforesaid tubes
or passages and the chamber or chambers
above, when the lamp is first started, are filled
with the oil, which, when the lamp is lighted,
passes from the said chamber or chambers
45 through an opening or openings or perfora-
tion or perforations in the upper part of the
wick-tube and supplies the oil to the wick
near to the lighted end thereof. The filling
of the tube or passage or tubes or passages

and chamber or chambers with oil in start- 50
ing the lamp may be done by removing the
burner and inverting it, and pouring the oil
into the tube or tubes or passage or passages,
or it may be forced thereinto by any suitable
forcing device by which oil can be forced from 55
the reservoir into the said tube or tubes or
passage or passages and chamber or cham-
bers, or closeable openings may be provided
for filling from above.

In order that our said invention may be 60
fully understood, we will now proceed more
particularly to describe the same, and for that
purpose shall refer to the several figures on
the annexed sheets of drawings, the same let-
ters of reference indicating corresponding 65
parts in all the figures.

Figure 1 is a sectional elevation of the up-
per portion of a lamp constructed according
to our invention, provided with a force-pump
for charging the burner with oil when start- 70
ing the lamp; and Fig. 1^a illustrates a modi-
fication. Fig. 2 is a view similar to Fig. 1,
but without the force-pump, the burner be-
ing charged with oil when starting the lamp
by removing the burner from the reservoir 75
and charging it with oil through the lower
open ends of the tubes, as hereinafter de-
scribed. Fig. 3 is a sectional elevation, and
Fig. 4 a plan illustrating means for closing
and opening the lower ends of the tubes by 80
which oil is conducted to the burner; and Fig.
5 shows a portion of a lamp provided with
only one depending tube and a suction device
for charging the burner with oil.

Referring to Fig. 1, the vase or oil-reservoir 85
A is provided with an internally-screwed
collar a², into which the burner-fitting B
screws. This burner-fitting contains or car-
ries a wick-tube a, the upper end of which is
provided on both sides with a perforation or 90
hole or perforations or holes covered with
fustian, mole-skin, or equivalent absorbent
material d, which may be held in position in
any suitable way—for example, by means of
frames d', soldered to the wick-tube, as shown. 95
This absorbent material is inclosed by an
outer casing, so as to form a chamber or cham-
bers C, surrounding or partially surrounding

the upper end of the wick-tube. Communicating with this chamber or with these chambers C are two tubes D D', which depend therefrom and extend to within a short distance of the bottom of the oil-reservoir A when the burner is in position therein. The portion of the wick which enters the oil-reservoir is inclosed by a sheath or cover a³, closed at the bottom, so that the wick has no direct contact with the oil contained in the reservoir A, the oil for burning being supplied to the wick through the tubes D D'. One of the depending tubes D' constitutes the delivery-pipe of a force-pump f, which is fixed to the burner-fitting B of the lamp for the purpose of charging the tubes D, chamber C, absorbent material d, and wick b with oil when starting the lamp. When filled with oil, the chamber C is air-tight. When it is desired to start the lamp, (the reservoir A being charged with oil,) the pump f is worked by means of the knob or handle v, fast on the rod v² of the piston v³ of the pump, the oil being drawn into the pump-cylinder from the reservoir through the suction-pipe v⁴ and valve w by raising the piston v³, and then by depressing the said piston the oil will be forced through the pipe D' into the chamber C, and through the absorbent material d to the interior of the wick-tube and also into the tube D. The chamber C, absorbent material d, and wick b, and the tubes D D' being thus charged with oil, the pumping operation is discontinued, and the lamp being lighted the oil will continue to flow through the tube D to the wick and will continue to burn until the quantity of oil in the reservoir is reduced to or nearly to a level with the lower ends of the tubes D D', unless the lamp be previously extinguished.

By inclosing the wick b, so as not to be in contact with the oil in the reservoir, accidents by explosions through overheating are prevented.

Fig. 1^a shows one-half elevation of a modification of the arrangement, in which the pump f, employed for charging the burner with oil, is not connected to the charging tube or passage D', as in Fig. 1, but is provided with faced nozzles or branches u, (one for each of the tubes, one only of which is shown,) onto which, when it is required to effect the charging, the lower ends of the tubes D D' may be brought by turning the burner partially round in its socket, so that the passages through the tubes D D' will coincide with the passages in the nozzles u. Then, by working the pump-plunger by means of the knob or handle v, the tubes D D' and chamber C and the absorbent material therein will be readily charged with oil drawn in by the valve w, after which the burner may be turned in either direction, so as to remove the lower ends of the tubes D D' out of communication with the passages in the nozzles u and into communication with the oil in the reservoir, the lamp being then ready to be lighted.

Should the chamber C, the absorbent material therein, and the tubes D become discharged of the oil, they may be readily recharged by turning the burner, so as to make the tubes communicate with the passages in the nozzles u and then working the pump.

In the arrangement illustrated by Fig. 2 the wick-tube a is open at the bottom, the wick b passing therethrough into the reservoir A. The said wick may, if desired, dip into the oil contained in the reservoir; but this is not necessary, as the wick-tube and wick need not descend below the burner proper. A feeding-wick of very absorbent material may be provided, if desired, to conduct sufficient oil to the wick b to keep it moist, it being attached at any suitable point to the wick b, and dipping into the oil in the reservoir. The upper part of the wick-tube is perforated and is surrounded by a chamber C, containing a perforated partition c, so as to divide the chamber into compartments d d'. In the inner compartment d is placed absorbent material, as aforesaid, while the outer compartments d' communicate with tubes or passages D D' communicating at their upper ends to the chamber C and extending downward therefrom into the oil to within a short distance of the bottom of the reservoir.

The burner-fitting is preferably connected to the reservoir by means of a bayonet-joint arrangement, as shown at f²; but, if desired, it may be screwed into the reservoir, as in the arrangement Fig. 1, or be otherwise connected thereto. To start the lamp, the burner B is removed from the reservoir A, which is then charged with oil, and the chamber C, the absorbent material therein, and tubes D D' are also filled with oil by inverting the burner-fitting and tubes and pouring oil into the tubes D D' until they, the chamber C, and the absorbent material therein are fully charged. The burner is then replaced and fixed in the reservoir by means of the bayonet-joint connection, and the lamp is ready to be lighted. When the lamp is burning, the oil will continue to flow through the tubes into the compartment d' of the chamber C, through the perforated partition c and absorbent material d, and the perforations in the wick-tube to the wick, and maintain the requisite supply to the burner until the quantity of oil in the reservoir is reduced nearly to a level with the lower ends of the tubes D.

In order to insure a charge of oil being retained in the tubes D D' and chamber C and the absorbent material when the lamp is extinguished and when the burner is removed from the reservoir for the purpose of supplying the latter with oil, the lower ends of the tubes D may be provided with means for closing their lower ends—such, for instance, as are shown by dot-and-pick lines in Figs. 3 and 4, which consists in pivoting to the lower end of each tube D D' a plate or valve g, on the under side of which is a projection h, engaging a guide slot or groove i, fixed or formed

in the interior of the reservoir A, so that when the lamp is extinguished, or when it is for other reasons required to close the tubes D D', this may be effected by turning the burner-fitting in the direction of the arrow in Fig. 4 from its position in which it should be when the lamp is burning until the edges k of the lips l on the rim l² of the burner-fitting come up to the points, marked k² on the rim m on the reservoir, in which position the ends of the tubes D D' will be closed by the plates or valves g, the lips l being still engaged with the projection or rim m on the reservoir, so as to keep the burner-fitting in contact therewith and prevent accident by its becoming detached.

In order to detach the burner-fitting from the reservoir, it is necessary to turn it still farther in the direction of the arrow, until the lips l pass the ends n n of the rims m m, and then the burner-fitting may be raised from the reservoir, the tubes D D' being still closed by the valves or plates g. When the burner-fitting is replaced on the reservoir, the projections h on the valves g enter the grooves or recesses i, and thus prevent the valves from moving with the tubes D D' when the burner-fitting is turned for the purpose of securing it to the reservoir. The valves, however, are of such a form as to maintain the lower ends of the tubes D D' closed until the edges k of the lips l have passed the points k² on the rim m, the said tubes not being fully open before the edges k of the lips l are brought against the stops at o, forming part of the rims m. When the burner-fitting is in this position, the lamp is ready to be lighted. On the rim of the reservoir A are guides or stops p, to insure the burner-fitting B being inserted in the reservoir in the proper place for the projections h on the valves g to enter the guides or slots or recesses i.

Instead of removing the burner-fitting from the reservoir for the purpose of charging the tubes D D' and chamber C and the absorbent material therein with oil, as hereinbefore described, there may be provided on the reservoir a stoppered tube, as shown by dot-and-dash lines at r in Fig. 3, communicating with the chamber C, so that oil introduced by the tube r will flow through the chamber C into the tubes D D'. When the chamber C, the absorbent material therein, and the tubes D D' are fully charged, the tube r is closed by the screw-plug ⁷², and the lamp is then ready to be lighted.

Fig. 5 is a sectional elevation of a portion of a lamp provided with only one feeding-tube D, (but more than one may be provided, if desired,) and having, instead of the force-pump hereinbefore described, a suction device for charging the burner with oil for the purpose of starting the lamp. This suction device consists of a chamber 1, secured to the burner and communicating by a tube or passage 2 with the chamber C, surrounding the wick-tube.

The chamber 1 is closed by a cover 3 of leather or other suitable flexible material secured to the chamber in any convenient manner—for example, by means of a rim 4, as shown in the drawings, soldered, screwed, or otherwise attached to the chamber. Inside this chamber is a spring 5, which bears against the inner face of the cover 3, and tends to force it outward.

The chamber 1 should be of sufficiently large capacity to draw the oil from the reservoir without returning it thereto; or we may employ a valve x at the lower end of the tube D, as indicated by dotted lines.

To charge the burner with oil, the cover 3 is depressed against the pressure of the spring 5 and then released, whereupon the spring will force the cover outward, thereby producing a partial vacuum, which causes the oil from the reservoir to flow up the tube D into the chamber C and through the perforations in the wick-tube to the wick. This operation may be repeated as often as required until the burner is sufficiently charged. The lamp being then lighted will continue to burn until the oil in the reservoir is exhausted.

Lamps constructed according to our invention are very safe and are capable of burning heavier oils having higher flashing-points than can be burned in lamps as generally hitherto constructed.

Having now particularly described and ascertained the nature of our said invention and in what manner the same is to be performed, we declare that what we claim is—

1. In an oil-lamp, the combination of the reservoir, the wick-tube perforated or provided with openings at its upper end, the chamber at the upper end of the wick-tube, the absorbent material in said chamber, and a pipe or passage connecting said chamber with the reservoir.

2. The combination, substantially as hereinbefore set forth, of the reservoir, the wick, the wick-tube perforated at its upper end, the chamber at the upper end of the wick-tube, the absorbent material therein, a tube or passage connecting said chamber with the reservoir, and a sheath protecting the lower end of the wick from direct contact with the oil in the reservoir.

3. In an oil-lamp, the combination of the reservoir, the wick-tube perforated at its upper end, a chamber at the upper end of the wick-tube, a pipe or passage connecting this chamber with the reservoir, and a suction device for charging the chamber and wick with oil from the reservoir, substantially as described.

THOMAS PENN.
